LATCHING DEVICE FOR HOPPER CARS

Albert E. Zimmer, Chicago, Ill., assignor to Enterprise Railway Equipment Company, Chicago, Ill., a corporation of Illinois

Application July 21, 1949, Serial No. 105,915

2 Claims. (Cl. 105—308)

1

This invention relates, generally, to latching devices and particularly to such devices for use in holding closed the doors of hopper cars.

Among the objects of this invention are: To provide new and improved means for latching a vertically suspended door in an inclined closed position; to arrange and construct the latch mechanism so that the necessary car clearance limitations are met; to provide a shouldered locking latch below the sloping floor of a car hopper and to extend it through the plane of the floor to engage a seat on an outer portion of the door; to construct the latch so that it clears a wall of a frame member underlying the floor of the hopper; to provide for manually releasing the latch; and to lock the latch in the closed position.

Other objects of this invention will, in part, be obvious and in part appear hereinafter.

This invention is disclosed in the embodiment thereof shown in the accompanying drawings, and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a view, in side elevation, of a hopper door in the open position and showing how it is mounted on a hopper of a hopper car and latched thereto, the view being taken through the lower portion of a hopper car, certain parts of which are shown in section, and the view illustrating approximately one-half the width of the car;

Figure 2 is a plan view of the latch assembly including the shouldered latch, operating shaft and operating handle assembled apart from the car;

Figure 3 is a view, in side elevation, of the shouldered latch shown in Figure 2;

Figure 4 is a view, in side elevation, of the hopper and door shown in Figure 1;

Figure 5 is a view similar to Figure 4 except the door is shown closed and certain parts are shown in section, the section being taken along the line 5—5 of Figure 1; and

2

Figure 6 is a detail sectional view taken along the line 6—6 of Figure 5.

Referring now particularly to Figure 1 of the drawings, it will be observed that the reference character 10 designates a conventional center sill of a hopper type railway car, only a portion of the sill being shown. Spaced from the center sill 10 and parallel thereto is a car side wall 11 between which is located a hopper 12. The hopper 12 is formed by an upper sloping floor 13, a lower sloping floor 14, a vertical inner side wall 15, Figure 6, and an outer sloping side wall 16. The floors 13 and 14 and the side walls 15 and 16 together define a trapezoidal hopper opening 17, Figures 4 and 6, which is bounded by a frame that is indicated, generally, at 18.

The frame 18 includes an upper beam portion 19 which is secured along the lower edge of the upper sloping floor 13 and a stirrup portion 20 which is generally T-shaped in cross section. As shown in Figure 6 the stirrup portion 20 includes a flat flange 21 which is positioned along the outer edges of the side walls 15 and 16 and also along the outer edge of the lower sloping floor 14. A web 22 extends outwardly from the flange 21. The upper beam portion 19 and the stirrup portion 20 may be secured in position by suitable means such as rivets 23.

As shown more clearly in Figures 1, 4 and 5 of the drawings, hinge butts 26 are formed integrally with and extend outwardly from the upper beam portion 19. Hinge pins 27 extend through the hinge butts 26 for interfitting with the upper ends of hinge straps 28 that may be secured by rivets 29 to the door 30. It will be noted that the door 30 is generally pan-shaped and that it completely closes the trapezoidal hopper opening 17 with its edges 31 turned inwardly so as to overlap the side walls 15 and 16 and the lowermost edge 40 of the lower sloping floor 14.

In considering means for holding the door 30 in the closed position, attention must be given to the allowable clearances which must be maintained between the parts of the car, the road bed and the rails. With these factors in mind provision is made for latching the door 30 closed and permitting it to be opened by providing a shouldered latch which is indicated, generally, at 33 in Figure 3. The shouldered latch 33 includes a support portion 34 which has a hub 35,

Figure 2, formed integrally therewith. The hub 35 may be secured by a rivet or pin 36 to a shaft 37 which may be journaled in suitable bearings 38 and 39, Figure 6, that are carried by the portion of the stirrup 28 which underlies the lower sloping floor 14. Any suitable means may be provided such as rivets 49 for securing the bearings 38 and 39 in position.

Referring again to Figure 3 of the drawings, it will be observed that the shouldered latch 33 has a reentrant portion 42 extending from the support portion 34. The purpose of the reentrant portion 42 is to clear the rearwardly extending portion of the flat flange 21 as illustrated more clearly in Figure 5 of the drawings. The shouldered latch 33 also includes a shank portion 43, preferably of I cross section, having a hook portion 44 at the outer end which has a locking face 45 the center of curvature of which is the center of the opening through the support portion 34 or the longitudinal axis of the shaft 37 when the latch 33 is assembled thereon. The radius of the locking face 45 is indicated by the broken line 46 in Figure 3. The hook portion 44 has an inclined surface 47 which facilitates the automatic movement of the latch 33 to the locking position shown in Figure 5.

It will be observed that the shank portion 43 interconnects the support portion 34 and the hook portion 44 of the latch 33. Also, as shown in Figure 5, the shank portion 43 extends through an opening 48 in the floor 14 and also an opening 49 in the door 30 which is aligned therewith.

The hook portion 44 of the latch 33 cooperates with a beam 50, Figure 1, for holding the door 30 in the closed position. As here shown the beam 50 comprises a flat plate portion or flange 51 which lies flat against the outer surface of the door 30 at its lower end and is secured thereto by rivets 52. An opening 53 is formed in the flange 51 which is coextensive with the opening 49 in the door 30. The opening 53 is defined by outstanding flanges 54 and a seat portion 55 along the upper edge having a curved surface for engaging the locking face 45 of the shouldered latch 33. The curvature of the seat portion 55 which is engaged by the locking face 45 is the same as that of this locking face, i. e., its center is at the center of the shaft 37 on which the latch 33 is secured.

With a view to preventing the escape of lading from the bottom of the hopper 12 when the door 30 is closed, an inverted U-shaped housing 56 may be secured, as by welding, to the lower sloping floor 12. Its out-turned end 57, Figure 5, is juxtaposed to the inner surface of the door 30 when it is closed. In this manner the openings 48 and 49 in the floor 14 and door 30, respectively, are closed when the latter is in the closed position. However, sufficient room is provided to permit the movement of the latch 33 to the unlatched position in a manner which will be described now.

Any suitable means may be employed for rocking the shaft 37 for moving the shouldered latch 33 from the latched position shown in Figure 5. As illustrated in Figure 2, an operating handle or socket 58 is provided in accordance with the present invention having a hub 59 which may be secured by a rivet or pin 60 so that the assembly is fast on the outer end of the shaft 37. A socket opening 61 extends through the operating handle or socket 58 for receiving a bar which provides the operator with sufficient leverage to rock the latch 33 to the unlatched position.

With a view to locking the latch 33 in the

latched position, a locking dog 62 which is generally semicircular in shape may be provided. The locking dog 62 is rockably mounted on a pin 63 which extends between brackets 64, Figure 6, which are secured on an extension 65 of the bearing 38.

The locking dog 62 may be provided with a laterally extending integrally formed stop 66 which, as shown in Figure 4, is arranged to bear against the nose portion 67 of one of the brackets 64 to hold the dog 62 in the unlatched position. As shown in Figure 5 the stop 66 engages the upper side of the bracket 64 to limit the movement of the dog 62 therebetween. As shown in Figure 5 the dog 62 holds the operating handle or socket 58 in the position where the shouldered latch 33 is in the latched position with the locking face 45 in engagement with the seat portion 55.

When the door 30 is to be opened, the operator swings the locking dog 62 from the position shown in Figure 5 to the position shown in Figure 4. Then he inserts a suitable bar in the socket opening 61 and rocks the operating handle or socket 58 together with the shaft 37 and shouldered latch 33 in a clockwise direction. Since the radius of curvature of the locking face 45 is such that the center is located along the longitudinal axis of the shaft 37, the movement of the shouldered latch 33 to the unlatched position is facilitated. As soon as the hook portion 44 clears the seat 55, the door 30 swings open under the influence of gravity and the force of the lading bearing against the same.

With the parts as illustrated in Figure 4, the door 30 can be swung to the closed position. The inclined surface 47 first engages the underside of the seat portion 55 and, on continued closing movement of the door 30, the latch 33 is swung downwardly in a clockwise position until the upper end of the inclined surface 47 clears the lowermost portion of the seat 55. Thereafter the weight of the operating handle or socket 58 and the portion of the latch 33 to the left of the longitudinal axis of the shaft 37 as viewed in Figure 2 is sufficient to counterbalance the portions to the right of this axis and to cause the latch 33 to be rocked in a counterclockwise direction to the latched position as shown in Figure 5. Thereafter the locking dog 62 is rotated to the locked position shown in Figure 5.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In a railway car having a hopper with a discharge opening and a door hinged along one side of said opening for closing the same, said hopper including a floor sloping downwardly towards said opening for directing lading thereto and said door being swingable to meet the lowermost edge of said floor in closed position, and a frame member having a flat wall underlying said floor; in combination, a shouldered latch for holding said door in closed position, and support means pivotally mounting said latch beneath said frame member, said latch extending through the plane of said door for engagement with said door and having a reentrant portion straddling said frame member.
2. In a railway car having a hopper with a discharge opening and including a floor sloping

downwardly towards said opening for directing lading thereto, in combination, a door hinged along the upper side of said opening and swingable to meet the lowermost edge of said floor in closed position and having an opening near the side opposite the hinge side, a seat portion at the upper side of said opening in said door, a shouleder latch pivotally mounted beneath said floor and extending through the plane thereof for extending through said door opening and engaging said seat portion to hold said door closed, the portion of said latch which projects through said door opening having an inclined surface for cooperating with said seat portion to move

said latch away from the former when said door is closed, and biasing means urging said latch toward said seat portion whereby the same is engaged automatically on closure of said door to lock the same.

ALBERT E. ZIMMER.
